UNITED STATES PATENT OFFICE.

EBENEZER A. W. JEFFERIES, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

GAS-PRODUCER.

1,255,015.

Specification of Letters Patent. Patented Jan. 29, 1918.

Application filed December 14, 1914. Serial No. 877,004.

To all whom it may concern:

Be it known that I, EBENEZER A. W. JEFFERIES, a citizen of the United States, residing at Worcester, in the county of Worcester and Commonwealth of Massachusetts, have invented a new and useful Improvement in Gas-Producers, of which the following, taken in connection with the accompanying drawings, in a specification.

10 The present invention relates to gas producers, and has particular reference to the disposition and support of the main shell, or fuel containing section, of devices of this class.

15 The developments of gas producer practice have led to the use of spreading and leveling devices for the surface of the bed of fuel; a highly efficient method of securing the desired spreading and leveling action 20 contemplates relative rotation between the body of fuel and the spreading device, whereby the latter is rendered effective with respect to all portions of the surface of said bed.

25 Another step in the development of gas producers resides in the automatic discharge of the ashes therefrom, and a preferred embodiment of apparatus for accomplishing this function provides a substantially radial

30 plow or scraper carried within the ash supporting section of the producer and having a sweeping action with respect to the contents of the same when relative rotation between said plow and ash support is produced, thereby crowding the ashes outwardly and delivering the same from the edge of said support.

The present invention provides a construction peculiarly adapted for the attainment 40 of both of the above enumerated mechanical operations in a gas producer. The essential features of my invention are fully set forth in the following description, and illustrated in the accompanying drawings, 45 in which—

Figure 1 is a vertical sectional view of the lower portion of a gas producer embodying my invention.

Fig. 2 is a plan view of the same, from the 50 plane of line 2—2, Fig. 1.

Similar reference characters refer to similar parts in both figures.

The numeral 1 indicates the lower portion 55 of a gas producing chamber, inclosed within a wall or shell 2 which constitutes

the fuel supporting section of the producer. The lower end of said shell, in accordance with approved practice, opens into a concentric ash support or pan 3 having a horizontal bottom 4, and flaring walls 5, which 60 surround, and are spaced from the wall of shell 2.

In the attainment of the desired relative rotation between fuel bed and leveling member in the one case, and between ash support and ash plow in the other case, it will be apparent that the simplification of the mechanism for imparting such relative rotation between the several parts, in the manner previously set forth, can be best 70 served by the rotation of the ash support 3 and fuel section 2 in unison. Under these conditions, the leveling member 6, shown conventionally in Fig. 1, may be suspended or otherwise supported from the stationary 75 cover section, not shown, of the producer, for the support of which the standards 7 are employed. The ash plow 8, pivoted concentrically with respect to the ash support 3, and normally rotating in unison therewith 80 by reason of its contact with the bottom 4, is designed to have its rotation interrupted at intervals, when it is desired to effect a discharge of ashes over the wall 5, as will be clearly understood. However, the operation of the plow 8 requires its sweeping and crowding action to be effective over the entire bottom surface of the ash support from center to periphery, and furthermore, the interposition of a stationary stop in 90 the path of plow 8, designed to interrupt its rotation and bring about the desired discharge of ashes, necessitates the preservation of a wholly free and continuous space between the wall 5 of the ash support and 95 the shell 2, as will be apparent. Hence, the rotation of the ash support 3 and shell 2 in unison demands a means of connection between the two parts which will not obstruct the sweep of the plow 8, nor interfere with 100 the intermittent interruption of the rotation of said plow.

In carrying out my invention, the ash support 3 is disposed for rotative movement upon a plurality of rollers 9. Any 105 suitable means, such as a rotating bevel pinion 10, meshing with an annular rack 11 on the under side of the bottom 4, may be employed to rotate the ash support. Said bottom 4 is formed with a concentric pas- 110

sage 12, which communicates in any suitable manner with a blast passage 13, opening upwardly through the supporting floor of the producer. A hollow casting 14, 5 forming a continuation of the passage 12, is secured upon the upper side of the bottom 4, and communicates with and provides for the support of a hollow spider casting 15, herein shown as having three hollow radial 10 arms 16, 16, 16, which serve for the distribution of the blast to the superposed bed of fuel.

The spider 15 preferably has a central aperture, not shown, with respect to which 15 a spaced circular cap 17 is effective in providing for an annular upwardly directed jet of blast through the center of the bed of fuel. Each arm 16 is formed with an elongated opening 18, with respect to which a 20 spaced rectangular cap 19 is effective in providing for a pair of upwardly directed jets of blast through the fuel bed in substantially radial planes.

Beyond the outer closed ends of the blast 25 arms 16 are provided projections 20, serving for the support of an annular mantle 21 having suitable stiffening webs 21'. The mantle is preferably angular in cross-section, as shown in Fig. 1, providing an annular base portion 22 which seats upon the 30 projections 20, and an offset superposed annular supporting portion 23, preferably disposed normal to the flaring wall 2 of the fuel section of the producer. Said annular 35 portion 23 of the mantle provides for the erection thereon of said wall 2, in the manner disclosed in Fig. 1, thereby supporting the entire weight of the shell or fuel containing section, which is thus caused to rotate in unison with the ash pan.

By the above described construction, the desired action of the ash plow 8 is permitted to be carried out under the most favorable conditions, and the mass of fuel 45 in the producer is caused to be under the continuous influence of the spreading and leveling member 6. A single driving gear for producing the requisite relative rotational movements between the several parts 50 is all that is required. The distribution of blast to the bed of fuel is rendered most effective by the provision of the equidistant blast arms 16, which, in addition, are utilized for the support of the shell or fuel containing section of the producer.

I claim,

1. In a gas producer, a rotating ash pan having an unobstructed ash supporting surface, and a fuel containing section carried 60 by said ash pan.

2. In a gas producer, a fuel section, an ash support below said fuel section and concentric therewith, said ash support having a wholly unobstructed surface from the center to the periphery thereof, and a 65 member connecting said ash support to said fuel section to constrain their rotation in unison.

3. In a gas producer, an ash pan, a fuel section above said ash pan, there being a 70 continuous and unobstructed space between the wall of said fuel section and the wall of said ash pan, and means for supporting said fuel section from said ash pan.

4. In a gas producer, an ash pan, a fuel 75 section above said ash pan, there being a continuous and unobstructed space between the wall of said fuel section and the bottom of said ash pan, and means for supporting said fuel section from said ash pan. 80

5. In a gas producer, an ash pan, a fuel section above said ash pan, there being continuous annular spaces between the wall of said fuel section and the wall and bottom of said ash pan, and means for supporting 85 said fuel section from said ash pan to permit the rotation of said parts in unison.

6. In a gas producer, an ash support having a wholly unobstructed surface from its center to its periphery, a member supported 90 centrally of said ash support, a fuel section carried by said member, and means for imparting rotation to one of said parts, whereby all of said parts will be rotated in unison.

7. In a gas producer, a rotating ash support, an annular member supported from the center of said ash support, and a fuel section carried by said annular member. 95

8. In a gas producer, a rotating ash support, a plurality of hollow blast arms supported 100 from the center of said ash support and rotatable therewith, and a fuel section carried upon the ends of said blast arms.

9. In a gas producer, a rotatable ash support having a central blast opening, a plurality of hollow blast arms communicating 105 with said opening, and supported at the center of said ash support, and a fuel section carried upon the ends of said blast arms.

10. In a gas producer, a rotating ash support having a wholly unobstructed surface from its center to its periphery, and a fuel section above said ash support and supported from the center thereof, whereby said parts will rotate in unison. 110
